UNITED STATES PATENT OFFICE

ANTHONY E. SMIDLEIN, OF NEW YORK, N. Y., ASSIGNOR TO BIGELOW SANDFORD CARPET CO., INC., A CORPORATION OF MASSACHUSETTS

DESIGN FOR A CARPET

Application filed October 28, 1932. Serial No. 45,807. Term of patent 3½ years.

To all whom it may concern:

Be it known that I, ANTHONY E. SMIDLEIN, a citizen of the United States, residing at New York city, in Westchester County and State of New York, have invented a new, original, and ornamental Design for a Carpet, of which the following is a specification, reference being had to the accompanying drawing, forming part thereof.

The dot and dash lines define the unit of the design. The upper left hand corner of the unit designated "B", is repeated at the unit designated "A", one-half the right hand vertical edge.

I claim:

The ornamental design for a carpet substantially as shown and described.

ANTHONY E. SMIDLEIN.
